UNITED STATES PATENT OFFICE.

BURR C. BALDWIN, OF HOLLYWOOD, CALIFORNIA.

CLOTHES WASHER.

Application filed October 31, 1923. Serial No. 671,922.

To all whom it may concern:

Be it known that I, BURR C. BALDWIN, a citizen of the United States, residing at Hollywood, in the county of Los Angeles 5 and State of California, have invented new and useful Improvements in Clothes Washers, of which the following is a specification.

My invention relates to clothes washers 10 and particularly to what is known as vacuum clothes washers.

The general object of my invention is to provide an improved vacuum washer which will be simple in construction, easy to manipulate and highly efficient in operation.

A more particular object is to provide a vacuum washer with two washer units which can be rocked and rotated, thus providing an easy washing movement for the washer and 20 enabling said units to be applied to the clothes at every point of the tub, whereby the clothes are easily, quickly and thoroughly washed.

Other objects and advantages will appear 25 hereinafter and while I show herewith and will describe a preferred form of construction, I desire to be understood that I do not limit my invention to such preferred form but that various changes and adaptations 30 may be made therein without departing from the spirit of my invention as herein-after claimed.

Referring to the drawing:

Fig. 1 is a plan view of my washer.

Fig. 2 is a side elevation thereof.

Fig. 3 is a bottom plan view of my washer.

Fig. 4 is a vertical section of my washer taken on line 4—4 of Fig. 1.

Fig. 5 is a side elevation of my washer 40 mounted in a tub shown in vertical section, and showing the washer swung to the right into one of its washing positions.

My washer includes two washer units 1 and 2, a frame 3 on which said units are 45 mounted, and a vertical handle 4. Each unit 1 and 2 comprises a casing 5, which is elliptical in cross section and converges upwardly, and a double elliptical member 6 mounted in the lower portion of said casing. The casing 5 has a flat horizontal wall 7. The frame 3 comprises an upper horizontal bar 9, spaced below said upper bar, and a tubular socket 10 which is secured at its lower end to the bar 9 and extends upwardly through the

upper bar 8 and is flanged over the upper surface of said bar at 11. The lower end of the handle 4 is fitted in the socket 10. The end portions of the bar 8 rest upon and are secured to the upper walls 7 of the units 1 and 2, while the ends of the bar 9 are secured to the side walls of the casings 5 of said units, whereby said units are mounted on the frame 3.

It is necessary to secure the ends of the parallel spacing and bracing bars 9 to the sides of the tapered casings 5, at a considerable distance from the bases of said casings 5, preferably about midway between bottom and top thereof, to keep said bar 9 60 out of contact with the clothes.

Therefore, it is also necessary to place said parallel members 8 and 9 relatively close together thus increasing the strain upon these members owing to the short fulcrum 75 necessarily provided for the handle 4. The sleeve 10 not only forms a socket for handle 4 but by having its ends firmly secured to the central portions of bars 8 and 9 braces said bars against the strain and makes it unnecessary to use a heavy cumbersome construction for this part of the appliance.

Each member 6 comprises a pair of vertical walls 12 and 13 and an upper wall 14, 85 the walls 12 and 13 being elliptical in cross section and the wall 13 being spaced within the wall 12 parallel thereto, and the wall 14 converging downwardly and being secured at its outer and inner edges to the upper ends 90 of the walls 12 and 13.

The members 6 are secured to the inside of the casings 5 of the units 1 and 2 at the junctures of the walls 12 and walls 14 as at 15. Unnecessary cross-walls or other uniting elements are thus dispensed with and the process of manufacture simplified by first making a washing element having the general shape of a double-walled container and then securing it in an inverted position, within the hollow washing unit 100 in the manner already described.

The upper walls 14 are provided with perforations 16 and the walls 12 are provided with openings 17 near the upper end thereof. The lower ends of the walls 12 and 13 lie in the same plane as the lower end of the casing 5. The walls 12 and 13 provide an elliptical vertical channel 18 between the wall 12 and the casing 5, an elliptical vertical channel 19 between the 110

walls 12 and 13, and a vertical passage 20 extending from the bottom of the casing 5 to a chamber 21 in the casing above the member 6.

5 The channels 18 and 19 and the passage 20 are open at the bottom. Openings 22 are provided in the casing 5 leading from the chamber 21 to the atmosphere.

In operation the washer is placed upon the 10 clothes in the tub 23 with the lower open ends of the units 1 and 2 downward. By means of the handle 4 the washer is rocked as shown in Fig. 5 and rotated. The downward movement of each unit 1 and 2 forces water 15 through the clothes up through channels 18 and 19 and passage 20, the water passing from channel 18 through openings 17 into the upper end of the channel 19 from which channel the water passes through openings 20 16 into chamber 21, while the water passes directly through the passage 20 into said chamber. Air escapes from the chamber 21 through the openings 22 to allow the water to enter said chamber. A vacuum is created 25 when the unit moves downward, which gives the clothes a pulling action when the unit

is moved upward, which action is very effective in removing the dirt from the clothes.

The rotation of the washer enables the units 1 and 2 to be applied to the clothes 30 all the way around the tub.

I claim as my invention:

1. A hollow tapered washing unit comprising an outer shell within which is contained an internal hollow member consisting of a pair of sleeves united at their upper or interval ends by a cross wall thus forming a washing element having the general shape of an inverted double-walled container, the peripheral portion of the internal end of said double-walled member being secured directly to the inner surface of said tapered unit. 35

2. The combination, with the hollow tapered washing units, of a pair of parallel bars, one of said bars being secured to and aligning with the upper ends of said tapered units, and the other of said bars having its ends secured to said units approximately midway between their bases and tops, and a bracing sleeve connecting the central portions of said parallel bars. 45 50
